JOSEPH E. FERLAND, OF LAWRENCE, MASSACHUSETTS.

TOY SAVINGS-BANK.

SPECIFICATION forming part of Letters Patent No. 627,727, dated June 27, 1899.

Application filed December 21, 1898. Serial No. 699,916. (No model.)

To all whom it may concern:

Be it known that I, JOSEPH E. FERLAND, of Lawrence, in the county of Essex and State of Massachusetts, have invented certain new and useful Improvements in Toy Savings-Banks, of which the following is a specification.

This invention has relation to toy savings-banks employing a receptacle for coins, a register operated by the insertion of a coin, and locking mechanism operated when a certain number of coins have been deposited to allow the coins to be removed.

The invention has for its object to improve the registering mechanism and devices for operating the same and also to improve the general structure of articles of this character, as will be more fully hereinafter described, and set forth in the claims.

Of the accompanying drawings, forming a part of this specification, Figure 1 represents a front elevation of a toy savings-bank constructed in accordance with my invention. Fig. 2 represents a vertical transverse section through the same. Fig. 3 represents a vertical longitudinal section through the same with the lower part of the casing omitted. Fig. 4 represents a detail perspective view of the spring member employed. Fig. 5 represents a detail view of parts shown in Fig. 3, illustrating the positions occupied by them after the insertion of a coin.

The same reference characters indicate the same parts in all the figures.

Referring to the drawings, *a* designates the casing, preferably composed of cast-iron and having its front, bottom, and sides in one piece, while the back *2* is made as a separate piece and engaged with the bottom of the casing by means of a dowel or projection *a'*, entering a hole in said bottom, the top edge of said back when in place taking under the upper edge *a¹⁵* of the main body. The back *2*, which may be said to constitute a door for the casing, is also normally locked to the main body of the casing by means of a spring-catch *a²*, having a hook *a³* at its forward end, which engages a pin or stud *a⁴*, projecting from one side of the casing and constituting a keeper for the catch *a²*. The lower part of the casing, as will be seen in Fig. 2, is constructed as a receptacle for the coins *b*. Said

coins are inserted in the bank through a coin-slot *a⁵* in the upper part of the front side of the casing. In order to prevent the insertion of a wire or other instrument to tamper with the index mechanism, presently to be described, a horizontal rearwardly-projecting shelf *a⁶* is shown as provided, forming the floor of the slot *a⁵*. The coin is inserted part 60 way in the slot and is then flicked or given a light blow with the finger to send it beyond the rear edge of the shelf *a⁶*, or the bank may be tilted backward until the coin slides over said edge. When the coin is inserted, it enters an upper chamber *a⁷* in the top of the casing, and in falling it strikes against an inclined lip *a⁸*, forming the bottom of the said chamber *a⁷*, and is guided thereby onto a lever *c*. The coin occupies an upright position when 70 it strikes said lever, being confined between the front of the casing *a* and the downwardly-bent lower end of the lip *a⁸*. The lever *c* is pivoted to a stud *c'* on the casing *a* and normally has its end 4 resting underneath an 75 abutment *6* on one side of the casing, while the heel 5 of the lever *c* is normally in the path of an abutment 7, formed on a slide *d*. The latter extends across the upper part of the casing, having one end guided by a recess 8, formed in one side of the casing, and the other end projecting through a slot 9 in the other side of the casing and bent up outside of the casing to form a handle or lip *d'*.

To the under side of the slide *d* is attached 85 by rivets *e' e'* one end of a spring member *e*, whose form is represented in Fig. 4. The extremity of the latter is bent downwardly to form a spring-pawl 12, which engages ratchet-teeth *f' f'*, formed on the edge of an index or 90 registering wheel *f*, the latter being pivoted on a stud *a⁹*, cast on the front of the casing *a*. The intermediate portion of the spring *e* is riveted to the side of the casing *a* by means of the keeper-stud *a⁴*, and its extreme lower 95 end is bent up and acts as a check-pawl 13 for the registering-disk *f*. A very narrow portion 10 of the spring member *e* extends upwardly and engages a pin *c³* on the heel 5 of the lever *c*, exerting a downward pressure on 100 said pin, which normally holds the lever in the position shown in Fig. 3.

a¹⁰ is an angular web cast integrally with the back *2* of the casing *a* and forming two

partitions 15 and 16, which are so disposed as to prevent the coins already deposited in the bank from getting lodged in the working mechanism when the bank is inverted or agitated. The web projects across the casing and at its angle abuts against and engages the stud a^9 .

The operation of the device is as follows: Normally the slide d is prevented from operating by the action of the lever c , which acts as a stop for said slide when no coin is present. When a coin is inserted, it depresses the end 4 of the lever, overcoming the tension of the spring 10 , which is very light, and moves the heel 5 of said lever out of the path of the abutment 7 on the slide d . The lever assumes the position represented by full lines in Fig. 5. The spring 10 straightens out and temporarily prevents further turning of the lever on its pivot, and the coin rolls down said lever until arrested between the lever and an abutment 14 on the casing a . Then upon the slide d being pressed inwardly by a person the spring 10 acts as a rigid positive connection between the slide and lever, turning the latter further on its pivot, as represented by the dotted lines in Fig. 5, and releasing the coin, which falls to the bottom of the casing, while at the same time the pawl 12 acts to rotate the registering-wheel f a distance of one tooth. Upon the pressure being relieved on the slide d the action of the upper end of the spring-piece e returns the slide to its initial position, and the spring 10 returns the lever c and relocks the slide.

On the face of the disk f , at its margin, are marked the numerals from "0" to "9," as seen in Fig. 1, said numerals being equally spaced around the disk and adapted to show one at a time through a slot a^{10} , formed in the casing. Above said slot, on the front of the casing a , are marked a second set of numerals from "0" to "9," these latter being closely spaced, so as to correspond to the distance between two of the numerals on the disk f . The latter has one hundred teeth, so that for each coin deposited the disk is moved through a space corresponding to one of the numerals on the casing a above the slot a^{10} . By inspecting Fig. 1 it will be seen that the numeral "0" on the disk f is below the numeral "5" on the casing a , indicating that five coins have been deposited. The said numeral "0" will move along as coins are successively inserted until it comes underneath the numeral "9" on the casing and will then disappear, while at the same time the numeral "1" on the disk will appear beneath the numeral "0" on the casing, indicating the insertion of the tenth coin. This indication proceeds in regular order, as will be readily understood, up to "99," after which the two characters "00" come into line, indicating the insertion of the one-hundredth coin. As the last or one-hundredth coin is inserted the casing is unlocked by means of a lip or projection f^2 ,

which is struck out of the margin of the disk f , coming into contact with the spring-catch a^2 and depressing the end of the latter out of engagement with the stud a^4 , thereby unlocking the back 2 from the main body of the casing. The casing may then be opened and the accumulated coins removed. When the casing is opened, complete access is also given to the inclosed mechanism.

It will be seen from the above description that I have provided a simple and inexpensive article of the character indicated and one not liable to get out of order easily or capable of being easily tampered with.

I claim—

1. In an article of the character specified, a register comprising a movable member marked with the numerals from "0" to "9," coin-controlled means for moving said member, and a stationary surface contiguous to said member and marked with the numerals from "0" to "9" in a space equal to the space between two of the numerals on said member.

2. In a device of the character specified, a manually-operated member, a coin-operated catch device adapted to be operated by the weight of a coin and to lock or release said member, an abutment arranged to form with the catch device an obstructed coinway in which the coin is arrested after the release of said manually-operated member, and a part connecting the catch device and the manually-operated member, whereby the latter is adapted to move the catch device to free the coin, said part being constructed as a spring to retract the catch device.

3. In an article of the character specified, a ratchet-wheel, a flexible spring check-pawl therefor continuously engaged with the wheel-teeth, and a coin-controlled operating-pawl therefor, the two pawls forming parts of one piece of metal.

4. In an article of the character specified, a ratchet-wheel, a manually-operated member, a retracting-spring therefor, a pawl acting on the wheel, said spring and pawl forming parts of one piece of metal, and coin-controlled means controlling the coaction of the manually-operated member and the ratchet-wheel.

5. In an article of the character specified, a ratchet-wheel, a pawl acting thereon, a coin-operated member, and a controlling-spring for said member, said spring and pawl forming parts of one piece of metal.

6. In an article of the character specified, a manually-operated member, a retracting-spring therefor, a coin-operated catch for said member, and a controlling-spring for said catch, said springs forming parts of one piece of metal.

7. In an article of the character specified, two movable members, one being coin-operated, and a connection between the two, said connection acting as a retracting-spring for one member, and also as a positive connec-

tion between the two members, whereby motion imparted to one member is transmitted to the other member through the rigidity of the connection.

5 8. In an article of the character specified, a rotary device, a coin-controlled manually-operated member, a retracting-spring therefor, a pawl operated by said member and adapted to actuate the rotary device, and a

check-pawl for said device, said spring and 10 pawls being parts of a single piece of metal.

In testimony whereof I have affixed my signature in presence of two witnesses.

JOSEPH E. FERLAND.
